UNITED STATES PATENT OFFICE.

CLARENCE W. COLEMAN, OF WESTFIELD, NEW JERSEY, ASSIGNOR TO THE HALL SIGNAL COMPANY, A CORPORATION OF MAINE.

RAILWAY-SEMAPHORE.

No. 882,928.

Specification of Letters Patent. Patented March 24, 1908.

Application filed October 31, 1905. Serial No. 285,271.

To all whom it may concern:

Be it known that I, CLARENCE W. COLEMAN, a citizen of the United States, residing at Westfield, in the county of Union and State of New Jersey, have invented certain new and useful Improvements in Railway-Semaphores, of which the following is a specification, reference being had therein to the accompanying drawing forming a part thereof.

10 My invention relates to semaphores such as disclosed in the Loree and Patenall Patent No. 733,981, dated July 21, 1903, wherein the semaphore-blade moves through the upper quadrant and the weight of snow and ice 15 upon the semaphore-blade, instead of being an element of danger, is an element of safety, increasing the normal tendency of the semaphore to the danger position.

My invention has for its objects to provide 20 a semaphore of this class in which the signal-lamp, which coöperates with the spectacles of the semaphore to give the light indications for night signals, is located on the side of the signal-post or support opposite to that at 25 which the semaphore-blade is located, as in the prevailing type of signals at present employed, and also to provide such a semaphore in which the spectacle portion of the semaphore, such portion being usually and 30 generally termed the spectacle-casting, is located largely on the side of the semaphore-pivot opposite to that at which the semaphore-blade is located when the semaphore is in the position of safety indication, per-

35 mitting the gravitational forces exerted by the semaphore-blade and the spectacle portion to be so opposed to each other that the semaphore may be moved with a constant impelling force in all positions; and also to 40 provide against the danger of disturbance of the normal tendency to danger position by reason of the breakage of connecting means between the semaphore-blade and spectacle, which at night would not be observable and 45 might result in a safety night signal where a danger night signal should be given by making such a semaphore-blade and spectacle portion integral or in one piece, as of wrought or sheet metal.

50 My invention also has for its object to provide a semaphore adapted for either two positions or three positions of indication and adapted for coöperation with a signal lamp held in either one of two positions.

55 Other objects of my invention will appear

from the following description of the apparatus embodying my invention which is illustrated in the accompanying drawings. I will now describe such apparatus, and will thereafter point out my invention in claims. 60

Figure 1 is a front elevation of a semaphore and the upper part of its supporting post, with the semaphore in the danger position. Fig. 2 is an end elevation of the same. Fig. 3 is a plan view of the same with the post 65 in section. Figs. 4 and 5 are front elevations of the parts shown in Fig. 1, with the semaphore in the two other positions of indication, Fig. 4 showing the caution or distant danger position, and Fig. 5 the safety 70 or clear position. Fig. 6 is an enlarged vertical section of the semaphore-blade taken on a plane indicated by the line 6—6, Fig. 1. Fig. 7 is a front elevation of a semaphore and the upper part of its supporting post, 75 this semaphore being of modified construction to adapt it for coöperation with a signal-lamp in either one of two positions and the post being of a construction wherein a lamp is centrally supported therein. Fig. 8 is a 80 front elevation of the same construction of semaphore, but with the standard form of post and lamp support. Fig. 9 is a front elevation of a semaphore of the same general construction as in Figs. 1 to 6, inclusive, but 85 with its pivotal center differently placed and adapted for coöperation with an up-and-down rod for pushing the semaphore to clear position, all other drawings illustrating constructions wherein the semaphores are pulled 90 to clear positions by wires or other tension means.

I will first describe the construction shown in Figs. 1 to 6, inclusive. Here the semaphore-post *a* is of standard construction, as 95 is also the signal-lamp *b*, and the signal-lamp is as usual supported on a bracket *c* at the side of the post opposite to that at which the semaphore-arm or semaphore-blade *d* is located. The semaphore comprises the blade 100 *d* and the spectacle portion *e*, these two portions of the semaphore being made integral or in one piece of sheet-metal, as sheet-iron or steel, beaded at its edges as usual in sheet-metal work and having a pivot-boss *f* which 105 may be welded or riveted thereto. Three spectacle-openings *g*, *y* and *r*, are formed in the spectacle portion, which are located so as to coöperate with the signal-lamp in the different positions of the semaphore. Spec- 110

tacles or colored or colorless glasses may be fitted in these spectacle-openings in any desired manner, or the spectacle-openings may be partly unprovided with spectacles, as may be desired, to adapt the semaphore to use as a three-position signal, a two-position home-signal, a two-position distant-signal, a switch-signal, or to any of the uses of a railway-signal. As shown, a spectacle is provided in each opening, which may be green at *g* for safety, yellow at *y* for caution and red at *r* for danger.

With the semaphore in the safety position, as shown in Fig. 5, the center of gravity of the spectacle portion *e* is located below the pivotal center of the semaphore, and as the semaphore moves to danger position, this center of gravity moves upward. The semaphore is secured to the semaphore-shaft *j*, on which is also secured a crank *k*; and an operating wire *l* is secured to the crank and operates to pull the signal to clear under the control of automatic or manually operated mechanism, as may be desired, with lever, gas, pneumatic, electrical or other operating mechanism.

The upper vertical or clear position of the semaphore is shown in Fig. 5. From this position it gravitates to the horizontal or danger position shown in Fig. 1 and its movement is arrested at this position by a stationary stop *m* on the signal-post engaging a stop-projection *n*, which may be welded to the semaphore. As will be seen, the semaphore-blade moves downward in approaching the danger position and its weight is at all times exerted in the direction of movement to the danger position and the weight of snow and ice upon the semaphore-blade only increases its tendency toward the danger position. It will also be observed that as the semaphore moves from the clear position to the danger position, the center of gravity of the semaphore-blade moves to the right with an increase of the distance between a vertical line passing through the pivotal center of the semaphore and a vertical line passing through the center of gravity of the semaphore-blade. Thus as the semaphore-blade moves from the vertical to the horizontal position, the leverage of its weight increases. It will also be seen that as the semaphore moves from the clear position to the danger position, the center of gravity of the spectacle portion of the semaphore moves to the left with an increase of the distance between a vertical line passing through the pivotal center of the semaphore and a vertical line passing through the center of gravity of the spectacle portion, and thus the weight of the spectacle portion is exerted in an opposite direction to the weight of the blade and the leverages of these opposed weights increase together and the relation of these two forces may be readily such as to produce a substantially constant

resultant force exerted upon the semaphore in all positions thereof, thereby permitting a comparatively small weight to be relied upon to move the signal to danger and therefore requiring the exertion of less power in clearing the signal and also materially diminishing the force required to arrest the semaphore at the danger position and diminishing the jar resulting from the contact of the stop-projection on the semaphore with the stationary stop on the semaphore-support. 75

The construction of semaphore shown in Figs. 7 and 8 is substantially the same as that heretofore described except that an additional semaphore spectacle-opening *o* is provided whereby the semaphore is adapted for use in connection with a signal-lamp, such as *b*, located in the usual position at the side of the post opposite to that at which the semaphore-blade projects, as shown in Fig. 8, or 80 to a signal-lamp, such as *b'*, located in the center of the post, as shown in Fig. 7, the post *a'* here shown being of modified construction to accommodate this placing of the signal-lamp. To adapt it to one or the other arrangement of signal-lamp, it is only necessary to change the positions of the colored glasses or spectacles.

In Figs. 7 and 8 the stop for the semaphore at danger position is shown as a stop-screw *q*, which is screwed into the post and arrests the movement of the semaphore by contact with the crank *k*. This provides a readily adjustable stop. A jam-nut *q'* locks the stop-screw in the position to which it is 100 adjusted.

The construction shown in Fig. 9 differs from that shown in Figs. 1 to 6, inclusive, in that the semaphore is arranged for actuation by an up-and-down rod *p*, which thrusts the semaphore to the clear position, this modification requiring the location of the pivotal center of the semaphore at a point at the left side of the post in order to locate the up-and-down rod medially in the post. Here the crank *k'* extends to the right and is thrust upward to move the semaphore to the clear position. A slight change in the positions of the spectacles is here required by reason of the alteration of the pivotal center. 110

The actuating mechanisms for the semaphores are not shown, as any ordinary or suitable actuating mechanism may be employed.

It is obvious that various modifications may be made in the constructions shown and above particularly described within the principle and scope of my invention.

What I claim and desire to secure by Letters Patent is:

1. The combination, with a semaphore-support, of a semaphore including a semaphore-blade and spectacle portion, the semaphore being pivotally mounted on a center at one side of the blade and supported so that 130

the blade is located at one side of the support, and a signal-lamp located at the other side of the support, the spectacle portion of the semaphore having a spectacle-opening disposed so as to coöperate with the lamp, and the semaphore being arranged so that the blade moves downward from the safety to the danger position.

2. The combination, with a semaphore-support, of a semaphore including a semaphore-blade and spectacle portion, the semaphore being pivotally mounted on a center at one side of the blade and arranged relatively to its pivotal center so that the blade 10 is at one side of the pivotal center and the spectacle portion is largely disposed at the other side of the pivotal center when the semaphore is in the safety position and so that as the blade moves downward from the 15 safety to the danger position, the center of gravity of the spectacle portion rises on the opposite side of the pivotal center and occupies, when the blade is in horizontal position, a position at a substantial distance in the 20 rear of the center, so that the spectacle portion has a counterbalancing effect when the 25 blade is in safety position.

3. The combination, with a semaphore-support, of a semaphore including an integral 30 semaphore-blade and spectacle portion, the semaphore being pivotally mounted on a center at one side of the blade and arranged relatively to its pivotal center so that the blade is at one side of the pivotal center and the 35 spectacle portion is largely disposed at the other side of the pivotal center when the semaphore is in the safety position and so that the blade moves downward from the 40 safety to the danger position.

4. The combination, with a semaphore-support, of a semaphore including a semaphore-blade and spectacle portion, the semaphore being pivotally mounted on a center at one side of the blade and supported so 45 that the blade is located at one side of the support, a signal-lamp located at the other side of the support, the spectacle portion of the semaphore having a spectacle-opening disposed so as to coöperate with the lamp, and 50 the semaphore-blade and spectacle portion being so arranged relatively to the pivotal center that the blade is at one side of the pivotal center and the spectacle portion is largely disposed at the other side of the pivotal center when the semaphore is in the safety position and so that the blade moves 55 downward from the safety to the danger position.

5. The combination, with a semaphore-support, of a semaphore including an integral 60 semaphore-blade and spectacle portion, the semaphore being pivotally mounted on a center at one side of the blade and supported so that the blade is located at one side of the 65 support, a signal-lamp located at the other

side of the support, the spectacle portion of the semaphore having a spectacle-opening disposed so as to coöperate with the lamp, and the semaphore-blade and spectacle portion being so arranged relatively to the pivotal center that the blade is at one side of the pivotal center and the spectacle portion is largely disposed at the other side of the pivotal center when the semaphore is in the safety position and so that the blade moves 70 downward from the safety to the danger position.

6. The combination, with a semaphore-support, of a semaphore including a semaphore-blade and spectacle portion, the semaphore being pivotally mounted on a center 80 at one side of the blade and arranged relatively to its pivotal center so that the blade is at one side of the pivotal center and the spectacle portion is partly at the other side of the pivotal center with its center of gravity below the pivotal center when the semaphore is in the safety position and so that the blade moves downward from the safety to the danger position and the center of gravity 85 of the spectacle portion moves upward during such movement.

7. The combination, with a semaphore-support, of a semaphore including an integral 90 semaphore-blade and spectacle portion, the semaphore being pivotally mounted on a center at one side of the blade and arranged relatively to its pivotal center so that the blade is at one side of the pivotal center and the spectacle portion is partly at the other side of the pivotal center with its center of gravity below the pivotal center when the 100 semaphore is in the safety position and so that the blade moves downward from the safety to the danger position and the center 105 of gravity of the spectacle portion moves upward during such movement.

8. The combination, with a semaphore-support, of a semaphore including a semaphore-blade and spectacle portion, the semaphore being pivotally mounted on a center 110 at one side of the blade and supported so that the blade is located at one side of the support, a signal-lamp located at the other side of the support, the spectacle portion of the semaphore having a spectacle-opening disposed so as to coöperate with the lamp, and the semaphore-blade and spectacle portion being so arranged relatively to the pivotal center that the blade is at one side of the pivotal center 115 and the spectacle portion is partly at the other side of the pivotal center with its center of gravity below the pivotal center when the semaphore is in the safety position and so that the blade moves downward from the 120 safety to the danger position and the center of gravity of the spectacle portion moves upward during such movement.

9. The combination, with a semaphore-support, of a semaphore including an integral 125

semaphore-blade and spectacle portion, the semaphore being pivotally mounted on a center at one side of the blade and supported so that the blade is located at one side of the support, a signal-lamp located at the other side of the support, the spectacle portion of the semaphore having a spectacle-opening disposed so as to coöperate with the lamp, and the semaphore-blade and spectacle portion being so arranged relatively to the pivotal center that the blade is at one side of the pivotal center and the spectacle portion is partly at the other side of the pivotal center with its center of gravity below the pivotal center when the semaphore is in the safety position and so that the blade moves downward from the safety to the danger position and the center of gravity of the spectacle portion moves upward during such movement.

10. The combination, with a semaphore-support, of a semaphore including a semaphore-blade and spectacle portion, the semaphore being pivotally mounted on a center at one side of the blade and arranged relatively to its pivotal center so that the blade is at one side of the pivotal center and the spectacle portion is partly at the other side of the pivotal center when the semaphore is in the safety position and so that the blade moves downward from the safety to the danger position, the spectacle portion being

provided with spectacle-openings adapted to coöperate with a signal-lamp in either one of two positions and with additional spectacle- 35 openings each adapted to coöperate with a signal-lamp in one only of such positions.

11. The combination, with a semaphore-support, of a semaphore including a semaphore-blade and spectacle portion, the semaphore being pivotally mounted on a center at one side of the blade and arranged relatively to its pivotal center so that the blade is at one side of the pivotal center and the spectacle portion is partly at the other side 45 of the pivotal center when the semaphore is in the safety position and so that the blade moves downward from the safety to the danger position, the spectacle portion being provided with spectacle-openings adapted to 50 coöperate with a signal-lamp at the side of the support opposite that at which the semaphore-blade is located and also with a signal-lamp immediately below the pivotal center of the semaphore with additional spectacle- 55 openings each adapted to coöperate with a signal-lamp in one only of such positions, substantially as set forth.

In testimony whereof I have affixed my signature in presence of two witnesses.

CLARENCE W. COLEMAN.
